The ornamental design for a shovel blade for a hand-held
implement, as shown and described.

DESCRIPTION

FIG. 1 is a top perspective view of a shovel blade for a
hand-held implement, showing my new design;
FIG. 2 is a top plan view thereof;

FIG. 3 is a side view thereof, the unshown opposite side
being of identical appearance;
FIG. 4 is a rear end view thereof taken from the left of FIG.
3;

FIG. 5 is a front end view taken from the right of FIG. 3; and,
FIG. 6 is a bottom view.
